CLAIM

The ornamental design for a disposable cardboard safety cone, as shown and described.

DESCRIPTION

FIG. 1 is a perspective view of the rear and right side of the assembled cone. The left side is a mirror image.

FIG. 2 is a front elevational view; and,

FIG. 3 is a plan view showing my design in an alternate, unassembled configuration.

In FIG. 3, the broken lines depict perforations or scoring, which form part of the claimed design.
